J. J. UNDERWOOD

ELECTRIC WATER HEATER

Filed Aug. 20, 1925

UNITED STATES PATENT OFFICE.

JESSE J. UNDERWOOD, OF TACOMA, WASHINGTON, ASSIGNOR OF ONE-HALF TO JOSEPH B. ANTONETTE, OF TACOMA, WASHINGTON.

ELECTRIC WATER HEATER.

Application filed August 20, 1925. Serial No. 51,358.

This invention relates to devices for electrically heating service water and especially to that class adapted for domestic use in heating the water in the hot water tank. The invention further relates to that class of electric water heaters wherein the heating element is immersed in the water being heated.

The objects of this invention are to improve the construction of such a heater whereby, first, the heating element may be withdrawn from the device without, in any way, disturbing the plumbing thereof; second, the base of the water heating chamber is removable therefrom without disturbing the plumbing thereof; third, said base fixedly supports the heating element within the heating chamber; and fourth, the electric junction box is integral with the heater base. Further objects are to improve the means of connecting the electric heating wire to the binding posts whereby a cheap, efficient and yet readily renewed electric connection is made; to improve the means of supporting the heating element from the base whereby said element is held in rigid position in the heating chamber; to improve the construction of the insulating supporting means whereby no portion thereof is permitted to become overheated; to provide a novel means for attaching the heating wire to the supporting insulating body whereby the heating wire is kept taut and is not allowed to sag thereon, and whereby the wires connecting the ends of said heating wire with the respective binding posts are relieved of strain; and to improve the means for passing the electric current into the water chamber without permitting leakage of the water therefrom. Another object is to provide an electric water heater which is simple and cheap to make, easily repaired, and efficient in use.

I attain these and other objects by the devices, mechanisms, and arrangements illustrated in the accompanying drawings, in which—

Fig. 1 is a vertical section of my improved water heater in use; and Fig. 2 is an elevation of the base and heating element removed from the water chamber. Similar

numerals of reference refer to similar parts throughout the several views.

Referring to the drawings it will be seen that the heater is constructed in two main parts, the water chamber 1 and the removable base 2.

The water chamber 1 comprises a hollow body of such dimensions as to receive the heater element and a sufficient body of water. It is provided with an inlet passage 3, near its lower edge, into which the cold water pipe 4 is secured, and with an outlet passage 5, at the top, into which the hot water pipe 6 is screwed. These pipes 4 and 6, respectively, lead from and to a suitable water supply and tank, or other desired connections with the plumbing system, and support the chamber 1 in fixed position. As readily seen from the drawings, the entire bottom of the chamber 1 is open and is adapted to be closed by means of the removable base 2 which is screwed into the open bottom thereof, suitable screw threads being formed in the lower end of the chamber 1.

The removable base 2 comprises an inverted cup-shaped hollow casting, having an upward extension 7 forming the bottom wall of the water chamber 1, and screw-threaded to screw into the lower end of the said water chamber. A shoulder 8 is formed outside of the said extension 7 and a suitable gasket 9 is mounted thereon, said gasket forming a watertight packing between the shoulder 8 and the lower edge of the water chamber 1 and preventing the leakage of water from the chamber by means of the screw threads connecting the two parts. The lower part of the base 2 is open, but may be closed by a removable plate 10 secured thereto in any desired manner.

The base 2 supports the heating element on its upper surface while the hollow box formed thereby forms the electric junction box wherein the conducting wires of the electric circuit are connected to the binding posts of the heating element; said binding posts passing through the upper closure wall of said base by means of insulating stuffing boxes.

Suitable bosses 11 are formed on the upper

wall of the base 2 and project downward into the junction box formed thereby. One of these bosses 11 is positioned centrally of said base 2, while the other is separated 5 therefrom to one side. The central boss forms the stuffing box and support for the central binding post 12 on which the electric element is mounted, as hereinafter described, and to which one end of the said 10 heating element is electrically connected, and the other boss 11 forms the stuffing box for the other binding post 13 to which the other end of the said electric element is secured. Each boss 11 is bored with a hole 14 slightly larger than the respective binding 15 post passing therethrough. Two pairs of insulating sleeves 15, of fiber or other suitable insulating material, are slipped over the conducting rods 12 and 13 within the hole 14 and a packing material 16, also of insulating material such as rubber or electric tape, is inserted between the two sleeves on such rod and is adapted to be compressed thereby to fill the hole 14 and prevent the 20 leakage of water therewith. Each conducting rod 12 and 13 is provided with an insulating washer 17 of mica, or other suitable material, and with a collar 18 engaging the said mica washer; said washer 17 and collar 30 18 being on the side of the said stuffing box which is inside the water chamber 1. The ends of said conducting rods 12 and 13 which project through the stuffing boxes and into the junction box are screw-threaded and provided 35 with mica insulation and washers and with two nuts 19 and 20. The nuts 19 are adapted to draw the respective rods tight against the top of the base 2 and to compress the packing 16, while the nuts 20 are adapted 40 to clamp the respective electric conducting wires 21 to the said rods. The cable containing the wires 21 enters the junction box through a suitable insulated passage 22.

The central binding post 12 extends a considerable 45 distance from the base 2 into the water chamber 1 and supports the two concentric insulators 23 and 24 thereon, the insulator 23 being positioned inside the insulator 24 and having an axial hole of larger 50 diameter than the post 12. The central hole of the outer insulator 24 is larger than the outside diameter of the insulator 23. Thus there is free space around the post 12 and between the two insulators for the circulation 55 of water, whereby all the several parts are kept from excessive heat and therefore insured against breakage from this cause. The outer insulator 24 is provided with a groove 25 around it, near its upper end, and 60 with a similar groove 26 near its lower end. A fastening wire 27 is tightly bound around the insulator 24, within the groove 25 and is led therefrom to the binding post 12 to which it is secured. A similar wire 28 is 65 tightly bound around the lower end of said

insulator 24 within the groove 26, and is led therefrom to the binding post 13 to which it is secured. The above described wires 27 and 28 are secured to the respective binding posts 12 and 13 by cutting a slit in the end 70 of said binding post, inserting the wire therein and bending the sides of said slit end of the binding post together to clamp the said wire therein. Thus it will be seen that the said insulators 23 and 24 are firmly 75 held in position by the binding posts 12 and 13 and by the wires 27 and 28 leading therefrom.

The heating wire 29 is preferably first wound into a long helical spring of small 80 diameter and then one end is attached to the said upper wire 27, above described, and the wire is coiled, helically, around the outside of the insulator 24, under sufficient tension to insure its holding itself in place, and the other end is similarly attached to the lower supporting wire 28. Thus it will be seen that the internal tension on the wire 29, necessary for it to have in order to properly maintain its position on the insulator, is carried by the wires 27 and 28 where they are bound around the insulator and is not carried to the binding posts. 90

It will therefore be clear that, when it is desired to take the heating element out of 95 the water for inspection, repair or replacement, it is only necessary to empty the said water chamber of its water, unscrew the base 2, and remove all the parts therewith, without disturbing the pipes 4 and 6 which 100 hold the water chamber in position and connect it to the plumbing system: also, that, when so removed, it is a simple matter to remove the heating wire 29 and to replace it with a new wire, by simply disconnecting 105 it with the wires 27 and 28; or the insulators may be removed by prying open the closed slits in the binding posts and removing the ends of the wires 27 and 28 therefrom.

Having, therefore, described my invention, what I claim is:

An electric water heater comprising a fixed water chamber provided with connections to the hot water system, whereby it is supported; a removable base closing the lower end of said water chamber and supported thereby, said base having a pair of passages therethrough; a pair of terminals passing through said passages, one such terminal being longer than the other, and each provided with a collar within said chamber and with a screw-nut on its outer end; a water-tight insulating packing in each said passage and surrounding the respective terminal, said packing being compressed within said passage by the screw-nut and the collar whereby leakage of water around the terminal is prevented; an inner insulating tube loosely surrounding the longer of said terminals whereby a free passage for water 120 125 130

is provided between the terminal and its mounted on said outer insulating tube; and insulator; an outer insulating tube loosely surrounding said inner insulating tube, whereby a free passage for water is provided between said inner and outer insulating tubes; a submerged electric heating wire

connections between the ends of said heating wire and said terminals respectively, whereby electric energy may be conducted to
